AUTOMOBILE WARNING LIGHT OR SIMILAR ARTICLE

Thure H. Wegener, Laurence Harbor, N. J.

Application May 3, 1949, Serial No. 2,409

Term of patent 3½ years

(CL. D72—1)

To all whom it may concern:

Be it known that I, Thure Henry Wegener, a citizen of the United States, residing in Laurence Harbor, in the county of Middlesex and State of New Jersey, have invented a new, original, and ornamental Design for an Automobile Warning Light or Similar Article, of which the following is a specification; reference being had to the accompanying drawing, forming a part hereof:

Fig. 1 is a side elevational view of an automobile warning light or similar article showing my new design, the cover thereof being shown in open position.

Fig. 2 is a rear elevational view thereof, and

Fig. 3 is a front elevational view thereof with the cover shown in closed position.

I claim:

The ornamental design for an automobile warning light or similar article, as shown.

THURE H. WEGENER.
